TEXTILE FABRIC

John Walther, Jr., New York, N. Y.

Application June 22, 1950, Serial No. 10,682

Term of patent 7 years

(Cl. D92—1)

To all whom it may concern:

Be it known that I, John Walther, Jr., a citizen of the United States of America, residing in New York, county of New York, and State of New York, have invented a new, original, and ornamental Design for a Textile Fabric, of which the following is a specification, reference being had to the accompanying drawing, forming part thereof.

The figure is a plan view of a textile fabric, showing my new design.

I claim:

The ornamental design for a textile fabric, substantially as shown.

JOHN WALTHER, JR.
